[57] ABSTRACT

The structural design of the Dyna-Shade relates to an umbrella wherein a covering material comprising the top is attached to a frame supported by one central column. The covering is in a plurality of levels thus giving the top a louvered appearance.

FIG. 10

FIG. 9

REF.
FIG. 10

DYNA-SHADE

The invention relates to a patio shade in that its primary purpose is to provide shade. The appearance of this invention is suitable to allow its use in a varied number of places. It is designed to provide a rigid and self-sustaining permanent shade which should be mounted in concrete. The objective of the louvered top is to decrease wind forces against the structure and to allow ventilation of heat. Other definite objects of this invention are that it is simple, it can be easily prefabricated, and it can be easily assembled with fasteners (in respect of its relatively large size) at the place of installation.

Other advantages and objects of the invention will be obvious during the course of the following specifications.

In the accompanying drawings, forming a part of this specification,

FIG. 1 is a side elevation view of the Dyna-Shade,
FIG. 2 is a plan view,

FIG. 3 is a section taken on line 3—3 of FIG. 2,
FIG. 4 (for optional construction) is a section on line

4—4 of FIG. 3,

FIG. 5 (for optional construction) is a section on line
5—5 of FIG. 3,

FIG. 6 is a section taken on line 6—6 of FIG. 3,

FIG. 7 is an orthographic projection from FIG. 6,

FIGS. 7a, 7b, 7c, 7d, 7e, and 7f are illustrations of optional shapes relating to FIG. 7,

FIG. 8 is a section taken on line 8—8 of FIG. 3,

FIG. 9 is an exploded oblique in part of FIG. 3, and,

FIG. 10 is an enlarged detail related to FIG. 9.

Referring to the drawings, the supporting one-piece column 11 should be inserted in concrete as shown in FIG. 3. A bracket 11a is welded to the column 11, a bracket 11b is welded to the top end of the column 11 and a threaded nut 11c is welded to 11b. For optional construction the supporting column 11 may be made of two separate pieces with a sleeve 11d welded to the upper portion of 11 and connected to the lower portion of 11 with fasteners as illustrated in FIG. 4 or it 11 may be made of two telescoping pieces connected together with fasteners as shown in FIG. 5.

The strut frame 12 is a weldment containing 12a, 12b, 12c, 12d, and 12e thus forming a plurality of offsets along its upper portion. For optional construction and the strut frame 12 can be an assembly having its parts joined together with fasteners as illustrated in FIG. 7e. The quantity of braces 12d and 12e required in each strut frame 12 is dependent on the overall length of the strut frame 12. The length of the strut frame 12 is dependent on the quantity of offsets 12c to be used (FIG. 7 - Ref.) and the length of strut segments 12a and 12b.

The lower portion of the strut frame 12 is connected to bracket 11a with a fastener, the upper portion (strut segment 12a) is slotted to slip over the top end of the wall of the column 11, the slotted bracket 11b locates and holds strut segment 12a in the proper place (FIG. 9 - Ref.) and the apex cover 20 acts as a retainer. A plurality of strut frames 12 are equally spaced completely around the column 11. For increased bracing the strut frames 12 are all connected together with brace members 13 and fasteners. To increase stability, lateral brace members 14 are connected to bracket 11a and strut frames 12 with fasteners.

The cover is broken into a plurality of levels and consists of a plurality of segments in each level. All covering segments 15, 16, 17, 18, and 19 are attached to the upper portion of the strut frames 12 (strut segments 12a and 12b) with fasteners. The quantity of covering segments in each level of the cover is equal to the number of strut frames 12 used. All covering segments of each level have a common size, shape, and hole pattern which matches the hole pattern in the respective levels of the strut frames 12. The longitudinal edges of the covering segments 15, 16, 17, 18, and 19 overlap above the strut segments 12a and 12b as shown in FIG. 6.

The physical shape of the covering material is thin and flat as shown in FIG. 7 or it may be corrugated as shown in FIG. 7f. With exception to the inner end of the top level covering segments 15, both ends (inner and outer) of all other covering segments may have optional shapes conforming to those illustrated in FIGS. 7a, 7b, 7c, 7d, and 7e.

The apex portion 20 of the cover is a conical disk (of thicker and stronger material than the covering segments) with a hole in its center and a pitch that coincides with the pitch of the cover. A screw 21 is placed through the hole in the apex cover 20 and screwed into a threaded nut 11c. The screw 21 is tightened against the apex cover 20 to form a compression type retainer for the inner ends of covering segments 15 and the upper portion (segment 12a) of the strut frames 12.

Having thus described my invention, I claim:

1. An umbrella-shaped shade-providing structure, comprising:

a central column adapted for attachment in the ground on the like;

a plurality of first radially extending frame members and a first column mount means mounting said first radially extending frame members onto said column;

each of said first radially extending frame members sloping downwardly from said first column mount means;

a plurality of second radially extending frame members and a second column mount means mounting said second radially extending frame members for lateral extension into connection with said first radially extending frame members;

a plurality of cover segments mounted on said first radially extending frame members; and

said first radially extending frame members having a plurality of offsets therein to provide offset strut segments for receiving said cover segments to form a plurality of offset cover segments which cooperate to provide shade while decreasing wind resistance and allowing the ventilation of heat.

2. The structure set forth in claim 1, including: said central column is a hollow, substantially cylindrical member adapted attachment in the ground or the like; and

a top bracket member mounted onto said cylindrical member, said top bracket member having slots therein for receiving said first radially extending frame members.

3. The structure set forth in claim 2, including: said first frame members having slots for engaging said cylindrical member with said first frame members being positioned in said top bracket slots,

4. The structure set forth in claim 1, wherein:

said central column includes telescoping inner and outer sleeve members.

5. The structure set forth in claim 1, including:
additional lateral brace members attached to said
second column mount means and to said first frame
members, said additional lateral brace members
being positioned in a non-radial direction with re-
spect to said column to increase stabilization of
said structure.

6. A new and improved shade structure, comprising: 10

a column having mounted thereon a frame structure
including radially extending, downwardly sloping
frame segments;
said frame segments having offsets therebetween;
and
cover segments mounted on said frame segments
such that said cover segments are radially offset to
provide a multi-directional ventilated shade struc-
ture.
